UNITED STATES PATENT OFFICE.

JOHN R. MILLAR, OF OAKLAND, CALIFORNIA, ASSIGNOR TO CALIFORNIA COTTON MILLS COMPANY, OF SAN FRANCISCO, CALIFORNIA, A CORPORATION OF CALIFORNIA.

QUILT AND MATTRESS.

1,221,890.

Specification of Letters Patent. Patented Apr. 10, 1917.

Application filed November 24, 1915. Serial No. 63,221.

To all whom it may concern:

Be it known that I, JOHN R. MILLAR, a citizen of the United States, residing at Oakland, county of Alameda, and State of California, (whose post-office address is No. 2439 Peralta avenue), have invented a new and useful invention—to wit, Quilt and Mattress; and I do hereby declare the following to be a full, clear, concise, and exact description of the same.

The invention is particularly adapted to the stuffing of quilts. The particular object is to prevent the fibers of the stuffing working out through the covering of quilts and mattress ticking, as will be hereinafter described.

Carded wool is acknowledged to be a superior stuffing for quilts and the like, because of its resiliency, its heat retaining qualities, and other advantages. Wool has one serious disadvantage, however, due to the penetrating tendencies of its individual fibers, resulting in these fibers working through the covering of quilts to the outside, resulting in the loss of the fibers as well as the unsightly appearance created.

Another disadvantage is the commercial impracticability of bleaching wool dead white. Its dull gray, drab color showing through the thin or filmy coverings of the quilts, detracting from the appearance thereof.

These several disadvantages are corrected by the interposition of a thin layer of carded cotton between the wool filler and the cover of the quilt. The clinging and the matting tendencies of the superimposed layer of cotton fibers presents an impediment that the fibers of the wool are unable to penetrate. The cotton has the further advantage of being cheap, pure white, agreeable to the touch and in itself a desirable stuffing substance, lacking however, some of the resiliency of the wool.

In this specification and annexed drawings, I illustrate the invention in the form that I consider the best, but it is to be understood that I do not limit myself to such form because the said invention may be embodied in other forms, and it is also to be understood that in and by the claim following the description herein, I desire to cover

the invention in whatever form it may be embodied. Referring to the drawings:

Figure 1 is a fragmentary perspective view of the corner of a quilt: the thickness being shown in cross section to illustrate the internal construction and arrangement.

Fig. 2 is a fragmentary detail in side elevation of a "bat" made up in accordance with this invention.

In detail the construction illustrated in the drawing includes the stuffing or core 1, of properly carded wool fiber, preferably consisting of superimposed layers built up to the desired thickness. This core is laid upon the under layer 2 of carded cotton. The core 1 is covered by the superimposed layer 3 of carded cotton. The edges 4 of the quilt are also provided with a protective layer 5 of carded cotton forming an integral part of the layers 2 and 3. The whole completely surrounding the core with a layer of material impenetrable to the fibers of the woolen core 1.

The bat thus formed is provided with the covering 6 of any suitable material, according to the quality of the quilt. The edges 4 are bound in the usual manner and the whole body of the quilt may be sewed, or tufted as at 7 in the usual manner. A quilt constructed in accordance with this invention has the following advantages: The covering may be of any light, translucent, flimsy material without disclosing the gray or drab tint of the woolen core. The underlying layer of cotton gives to the surface of the quilt a soft, silky, yielding sensation to the touch, while the quilt as a whole retains all the advantages of a woolen stuffing, without any of its disadvantages.

While I have described this invention in connection particularly with its use in quilts, I do not wish to be understood as confining myself to that particular application, inasmuch as the same advantage would follow its use in stuffing mattresses, clothing, or other pads, in which it is desirable to use wool fibers and retain them or prevent their working out through the surface of the bat or other articles.

The bat illustrated in Fig. 2, has a variety of uses common to cotton batting or woolen batting. The proportions of wool to cotton

can be varied to suit the particular requirements of its application.

Having thus described this invention, I claim:

- 5 A pad including a core of woolen fibers; a retaining layer of cotton fibers forming a loose bat and surrounding the core; a fabric cover; and ties passing through said pad.

Copies of this patent may be obtained for five cents each, by addressing the "Commissioner of Patents, Washington, D. C."

In testimony whereof, I have hereunto set my hand at Oakland, California, this 28th 10 day of October, 1915.

JOHN R. MILLAR.

In presence of—

BALDWIN VALE,
LINCOLN V. JOHNSON.
